INVENTOR.

W.D. Palmer

BY

A. Randolph, Jr. ATTORNEY.

UNITED STATES PATENT OFFICE.

WILLARD D. PALMER, OF NEW LONDON, CONNECTICUT.

TRUSS.

Application filed August 11, 1920. Serial No. 402,750.

To all whom it may concern:

Be it known that I, WILLARD D. PALMER, a citizen of the United States, residing at New London, in the county of New London and State of Connecticut, have invented certain new and useful Improvements in Trusses; and I do hereby declare the following to be a full, clear, and exact description of the invention, such as will enable others skilled in the art to which it appertains to make and use the same.

The object of the invention is to provide a simple and relatively inexpensive truss and more particularly a pad and means for holding the same in place under conditions affording the minimum of inconvenience to the wearer with the maximum of security against displacement and hence the release of the hernia, regardless of the muscular movements or postures of the body in connection with which the same is employed, and with these objects in view, the invention consists in a construction and combination of parts of which a preferred embodiment 25 is shown in the drawings, wherein:—

Figure 1 is a front view of the device in its applied position,

Figure 2 is a longitudinal sectional view of the same, enlarged to show the specific 30 construction of the pad.

Figure 3 is a rear view of the device in its applied position.

The pad 10 in surrounding or encircling relation with the bearing knob or button 11 is provided with an annular cup 12 bounded by a peripheral flange 13, the cup serving as a means of affording a suction to maintain the pad in its proper relation to the hernia and prevent displacement due to 35 movements of the body. In addition to this means of holding the pad in place, there is employed a belt 14, as in the ordinary practice, fitted with an adjustable fastening means such as the buckle 15, to which is attached the supporting ring 16, and carried by this ring are the spring fingers 17 and 18 of which the former is provided with a terminal ball 19 fitted in a socket 20 in the back of the pad, the free end of the spring 40 being arranged to bear against the corresponding end of the spring 17 so as to supplement the pressure thereof in holding the pad in place.

While it is well recognized that it is not new to employ yielding or spring means for holding a pad in place, and as such means are ordinarily necessary in order to provide for the movements of the body of the wearer, it is also a well known fact that such means of retaining the pad do not prevent slight 55 movements in one direction or another of the pad and hence a gradual displacement of the latter with relation to the hernia. Such slight displacement or movement in one direction or another of the pad is prevented 60 by the cupping thereof as above described, and therefore while the spring or yielding bearing members 17 and 18 provide for the more extensive movements of the pad due to those of the body of the wearer, the cupped 65 form of the pad serves to maintain the latter in its proper relation to the hernia when slight movements of the body are made or to prevent displacement of the pad by reason of muscular movements which are insufficient to displace the pad bodily and therefore would be resisted by the yielding fingers, but tend to move the pad laterally with 70 relation to the hernia and thus destroy its efficiency. The construction indicated in 75 other words maintain an intimate bearing of the pad upon the flesh of the wearer and the yielding fingers therefore may be relied upon essentially to exert the pressure necessary to hold the hernia in place rather than 80 to maintain the pad in proper relation thereto.

Having thus described the invention what I claim is:

A truss having a pad provided with a 90 socket, a belt in sections, a ring, fingers, means securing the sections and fingers to the ring, said fingers being flexible, overlapping and unconnected to each other within the opening of said ring for relative movement, and a ball extending from one of said 95 fingers and swivelled in said socket.

In testimony whereof I affix my signature in presence of two witnesses.

WILLARD D. PALMER.

Witnesses:

CHARLES H. WOODSTOCK,
ALBERT A. WILLIAMS.
